SPRAY HEAD CORE BOX BLOW TUBE

Edwin F. Peterson, Neponset, Ill.

Application August 29, 1955, Serial No. 531,042

1 Claim. (Cl. 22—10)

This invention relates to an improvement in sand conducting core blowing tubes of the character generally employed to convey sand under pressure from a sand supply source into the interior chamber or cavity of a core box.

More specifically this invention is directed to a sand arrester type of blow tube that is constructed and arranged for delivering a multistream pressurized sand discharge throughout a core box cavity and to directionally scatter the sand over a large percentage of the interior surface contour of the core box in filling the latter.

Core boxes are comparatively expensive and proportionally so to the particular intricate nature of each box as judged from its designed purpose. A core box may consist of two or more cooperative matched sections and it may be of the character wherein the core forming cavity is complicated to provide for the production of unique or special core designs. Anything that can be done to lengthen the practical useful life of such a box provides a substantial saving in operating costs in foundry practice and results in better monetary returns due to a more efficient production average in the process of fabricating cores.

One of the objects of the present invention is to provide a core blowing tube that will not, as in the past, repeatedly discharge a single concentrated pressurized sand stream that will impinge full force against the same opposite wall area of the core box, but to provide a sand blowing tube that will provide a divided discharging sand spray directed into the core box cavity under the same pressurized conditions and sand feed arrangements as heretofore employed.

This distribution of the sand conveyed through one fixed capacity pressurized conduit feed by division into a plurality of finer sand discharge sprays of smaller sand feed quantities under the actuation of a proportional amount of the total fluid pressure for each spray, establishes a better and faster sand filling cycle for a core box and concurrent with this action, the wear action of the abrasive sand material is practically negligible as far as affecting the interior contour of any given area of the core box chamber is concerned.

It is another object, therefore, of the present invention to provide a better and more uniform sand distribution into all corners and contiguous cavity portions of the interior of a core box.

Another object of the invention is to provide an apertured spray head type of blow tube that is connected between a sand supply source and a core box and which is provided with a rounded head that is operatively disposed within a given part of a core box cavity to position the head apertures within the cavity of the core box and to introduce a 180° spray of sand about the axial end of the tube into the core box cavity and through a 360° area about the blow tube axis.

As a further object, the blow tube of this invention may be used for granular dry sand discharge or for the discharge of conventional green sand mixes, the tube also

2

featuring a composite construction of metal and rubber, or metal and wear resistant material, with the rubber or wear resistant material forming that portion of the tube that divides the main sand stream of the tube and discharges the divided sand sprays into the core box interior.

It is an object of this invention to also provide a sand blowing tube that includes the divided spray features of the tube designed, but which tube is designed for directing various sizes of sand streams in predetermined directions within a given cavity configuration of a core box. Under the same conditions the tube is constructed to include orientation means to fix the position of the tube in a given relation to the sand blowing head or blow plate opening so as to also occupy a given relation to the core box openings for said tube. Matching orientation means may be carried by the blow head, the core box or by both to coact with the orientation means of the tube thus providing a way to preposition the sand discharge openings of the tube within the core forming cavity of the core box.

Further objects and features of the present design of blow tube reside in the symmetrical contour and shape of the discharge head, the nature of the openings therein and their arrangements.

Other objects and advantages relating to the blow tube of this invention shall hereinafter appear in the following detailed description having reference to the accompanying drawings forming a part of this specification.

In the drawings:

Fig. 1 is a vertical cross sectional view of a separable section core box incorporating a spray head blow tube of the present invention;

Fig. 2 is a fragmentary vertical cross sectional view of a portion of the Fig. 1 construction illustrating a formed core with the blow tube partially withdrawn therefrom;

Fig. 3 is an enlarged vertical axial cross sectional view of a portion of a blow tube constructed according to the principles of the present invention depicting the tube shown in Figs. 1 and 2 and illustrating certain details of construction thereof;

Fig. 4 is a bottom plan view of the blow tube illustrated in Fig. 3;

Fig. 5 is a fragmentary side elevational view of a modified construction of spray head blow tube partially broken away and illustrated in section to show some of the interior details of the tube;

Fig. 6 is a bottom plan view of the blow tube shown in Fig. 5;

Fig. 7 is a fragmentary side elevational view of still another modified construction of blow tube being partially broken away and shown in section to indicate the details of construction thereof;

Fig. 8 is a bottom plan view of the blow tube illustrated in Fig. 7;

Fig. 9 is a vertical cross sectional view of a core box supported on a core making machine table and in operative sand receiving position against a sand blowing head, this arrangement incorporating a sand blowing tube of the Fig. 7 construction but provided with openings similar to the tube of the Fig. 3 construction;

Fig. 10 is a fragmentary plan section taken substantially along the plane of the line 10—10 in Fig. 9;

Fig. 11 is a fragmentary plan view of a portion of the core box in Fig. 9; and

Fig. 12 is a fragmentary bottom plan view of a portion of the blow head structure.

In Fig. 1 a core box is generally illustrated at 1 comprising an upper section 2 and a lower section 3 suitably joined along a parting line 4 to provide an interior cavity 5, with the core box being suitably positioned on the table 6 for vertical movement to

ward and away from the blow plate 7 of a sand box 8 containing core sand 9. At least one of the core box sections carries suitable air vents 2a with vent plugs 2b located as shown.

A blow tube 10 is positioned in fixed relation in aligned openings 11 in the blow plate 7 and 12 in the upper wall 13 of the upper section 2 of the core box 1. The head end 14 of the tube projects or depends into the core box cavity 5 and is provided with a plurality of sand discharging openings 15 through which core sand is discharged in streams to form the finished core of the kind which is fragmentarily shown at 16 in Fig. 2. When the two sections of the core are separated a hemispherical recess 17 will remain in the core, this recess being formed by the shape of the projecting head 14 of the blow tube 10. This cavity 17 may be subsequently patched or it may be located in a core print section as more fully described in my copending application Serial No. 530,961, filed of even date herewith.

Referring now more specifically to Figs. 3 and 4, the blow tube 10 comprises a metallic conducting section 18 providing a hollow body which is joined by a bonded flanged arrangement 19 to a resilient or wear resistant head 20 carrying the openings 15 previously referred to. As shown in Fig. 4, the openings 15 are well scattered about the hemispherical head 20 so as to provide a full 180° of sand spray discharged into the mold when considered in a plane axially disposed with respect to the tube position and a 360° sand spray in a radial direction about the tube end in the core cavity.

The hemispherical head 20 is constructed from rubber or from other tough but resilient wear resistant material so that this tip, which transforms the main sand stream under pressure being conducted through tube section 18, is readily adapted to sustain the wear of the abrasive material and to separate this sand stream into a plurality of finer streams that are discharged through the openings 15 in the head 20. Each of the individual sand streams carry their own proportionate share of the total fluid pressure confined and directed through tube 18 so that the entire pressure arrangement and discharging abrasive material is widely distributed throughout the interior cavity of the core box 1 to substantially reduce wear of the interior walls of the core box to a minimum and negligible value.

The tube shown in Figs. 5 and 6 is proportioned as a bullet head 21 with the head comprising a resilient wear resistant material or a material that will counteract wear by the abrasive material. In this particular form of the invention a plurality of slits 22 such as shown in Fig. 6 are provided radially with respect to the axis of the tube and extend from a central closed end portion of the tube tip thereof upwardly and outwardly to substantially the full diameter of the tube structure. In this form, the individual segmental parts 23 consist of a plurality of bands that will all bulge open outwardly under action of the internal fluid pressure to open the slits 22 to provide a discharge about the bottom of the tube end as indicated by the dot and dash lines 24 in Fig. 5. At the same time the discharge will also be 360° radially of the tube axis causing, in effect, a sand cloud under pressure that fills the core box.

In the form of the invention illustrated in Figs. 7 and 8 the blow tube is provided with a truncated cone end 25 that is made of wear resistant or resilient material as in the forms shown in Figs. 3 and 5. In the latter construction the head 25 is provided with a plurality of slits 26, 27, 28 and 29 establishing a plurality of segmental parts such as 30, 31, and 32 which are all adapted to open outwardly under internal fluid pressure supplied to the tube structure to discharge the tube sand into the core box cavity.

It should be noted that the slits 26 are of a predetermined length and equally spaced about the upper half portion of the tube as it appears in Fig. 8. Slits 28 and 29

are also of equal length but are shorter than slits 26 and are staggered vertically, while the slit 27 may be of a different length. At the same time the angularity between slits 26 is different from the angularity between the other group of slits 27 to 29 all of which provides a predetermined pattern of sand distribution for the particular accommodation of a given internal configuration of core box.

Thus, the various forms of spray head core box tubes are all devised for sand spray distribution outwardly of the tube tips and substantially about the 180° of the end of each of the tube heads and also in an area considered 360° radially of such heads with all of the sand discharge points being located within the cavity of the core box per se. The impression 17 left in the formed core 16 as shown in Fig. 2 may easily be patched after the core is formed or else the tube locations may be so chosen as to coincide with a core print area as previously mentioned.

With a predetermined positioning of the tube and with a predetermined chosen design of openings or slits, such a tube or tubes may be well adapted to a particular irregular shape of core box and to function efficiently and quickly to fill such a box with core sand with certain areas of the tube discharging greater quantities of sand in one direction while other portions of the tube will discharge different quantities of sand in still other directions within the core box.

The blow tubes are therefore well adapted to provide the most efficient arrangement for filling a core box quickly, adequately and with substantially insignificant wear considered in the light of the normal life of a core box as determined by other factors of damage and wear during use. Graphically, Figs. 9 to 12 illustrate the principle as applied to a tube having placed sand discharge openings of certain sizes all adapted for use in blowing cores in the core box 33 shown.

The core box 33 comprises upper and lower sections 34 and 35 aligned by pins 36 at the parting line 37 with cavity portions such as 38, 39 and 40 providing the contiguous core forming chambers. Section 34 has vents 41 and 42 with vent plugs 43 in vents 42. The upper end of section 34 is flanged at 44 for connection with the blow plate 45 of the blow head 46 carrying core sand 47, while the section 35 is flanged at 48 for lug means 49 that secure section 35 to the vertically movable table 50 of the core making machine.

A blow tube 51 of the present inventive design is fitted into an opening 52 in blow plate 45 and depends through opening 53 in core box section 34 into the cavity 38. Tube 51 has a head 54 provided with two smaller sand discharge openings 55 at certain peripheral positions on the truncated wall 56 of the head and a larger sand discharge opening 57 oppositely arranged on another portion of the truncated wall 56.

With this arrangement of openings and their locations on the head of the blow tube 51 and on the tapered wall of the head as shown, sand streams 58 and 59 match the directions of the long hollow configurations of the core box and with the force of the sand streams and quantity of lessened sand discharge, wear by impingement is substantially eliminated while filling of the core box is more efficiently provided in reduced time cycles.

In the construction and arrangement described it is necessary to orient the tube with respect to the core box to arrive at the results indicated. For this purpose the tube may be marked "4x" to go with box 33 also so marked as shown in Figs. 9 and 11 respectively. Then the tube 51 is scribed or otherwise marked to show a line 60 adapted for alignment with either a reference mark or line 61 on the core box 33 or 62 on the blow plate 45 or the tube can be aligned with both if that is desirable. Fundamentally, the orientation means is provided to obtain the proper position of the tube relatively upon its axis to preposition the sand discharge

openings in the head in given relation to the core box 33 as best determined by the extent and locations of the interior cavities of the core forming box.

The foregoing disclosure and description has been directed to preferred forms of the invention and it is contemplated that certain changes may be made in the individual elements or in the combination of elements of such tubes without departing from the fundamental concept of the invention. Such modifications, however, shall be restricted in breadth and scope according to the language set forth and defined in the following appended claimed subject matter.

What I claim is:

In combination with a core box having walls to outline and to define an internal core forming cavity with an upper wall of the core box containing an access aperture extending therethrough and into an intermediate portion of said internal core forming cavity, a sand conducting tube having a rubber tip extending through said upper wall aperture of said core box and depending freely in said core forming cavity in freely suspended relation therein, said tip having a portion lying within said aperture, a closed end lying within said cavity, and a portion lying within said cavity having an outer wall converging towards said closed end and containing a plurality of radially disposed discharge slits unequally spaced from said end and peripherally about said tip to directly communicate with said cavity from a point within said cavity to direct sand in a plurality of directions having both radial and axial components from said dis-

charge opening into said cavity, whereby the introduction of sand under pressure through said tube tends to produce a seal between said core box and tip.
